UNITED STATES PATENT OFFICE.

EMIL F. HERRMANN, OF LOUISVILLE, KENTUCKY.

CANOPY ROCKING FAN.

1,201,962.

Specification of Letters Patent. Patented Oct. 17, 1916.

Application filed June 1, 1914. Serial No. 842,333.

To all whom it may concern:

Be it known that I, EMIL F. HERRMANN, a citizen of the United States, residing at 644 Baxter avenue, Louisville, in the county 5 of Jefferson and State of Kentucky, have invented a new and useful Canopy Rocking Fan, of which the following is a specification.

This invention relates to fan attachments 10 for chairs or the like and has for its principal object to provide a fan which is actuated by the rocking movement of the chair.

Another important characteristic of this 15 invention resides in the provision of a fan, an oscillating blade and a set of rotary blades, the oscillating blade imparting motion to the rotary blades.

Another object of this invention is to provide a device of this character which is simple, durable and efficient in its construction 20 and which may be manufactured at a nominal cost.

With these objects in view, others will 25 appear as the following description is taken in connection with the accompanying drawings; in which—

Figure 1 is a front elevation of my device 30 showing the same attached to the back of a chair. Fig. 2 is a side elevation showing the chair in section. Fig. 3 is a modified form of my invention showing a weight in the place of the oscillating fan blade.

Referring to the drawings in detail 1 designates a top rail of the back of a rocking chair of any common construction on which 35 is secured a bracket 2. This bracket 2 is preferably formed of wood and is substantially L-shaped as shown in Fig. 2. One 40 extremity of the bracket is bifurcated to provide the divergent legs 3, the lower extremities of the legs being formed with substantially U-shaped feet as at 4, the feet engaging the rail 1 and held in rigid position 45 thereupon by means of the set screws 5. Owing to the peculiar shape of the bracket it will be seen that when the same is in applied position upon the chair the free extremity thereof will be disposed directly 50 above the seat of the chair.

Vertically arranged upon the free extremity of the bracket and intersecting the same at right angles is a U-shaped yoke 6. One of the arms of the yoke 6 is extended 55 through the bracket at a point remote from the free end thereof as at 7, while the re-

maining arm is secured to the free end of the bracket as at 8. Thus it will be seen that the semicircular portion of the yoke is disposed upon the upper side of the bracket 60 while the extremities of the arms are disposed upon the under side. To form a rigid support for the yoke and to keep the same in proper position upon the bracket, I have provided the latter with a bearing plate 9, 65 the same being of U-shaped formation and having the free ends thereof secured to the upper sides of the bracket, while the upper end thereof engages the medial portion of the yoke 6. The opposite sides of the bearing plate 9 are provided with alined bearings in which is journaled a shaft 10, the shaft being arranged at right angles to the bracket and having its opposite extremities 70 provided with fan blades 11 which are 75 of any suitable construction. Pivotally mounted upon the bracket and between the parallel arms of the yoke 6 is the upper extremity of a fan blade 12, the same depending from the bracket and adapted to oscillate when rocking movement is imparted to the chair. Wound about the shaft 10 is a cord 13 the extremities of which are trained around pulleys 14 journaled in the ends of the yoke 6, and have their extremities 80 secured to the opposite sides of the fan blade 12.

It will be seen from this construction that when oscillatory motion is imparted to the blade 12 the cord 13 will be moved over the 90 pulleys 14 whereby rotary motion will be imparted to the shaft 10 to cause the fan blades 11 to rotate first in one direction and then the other, the direction of rotation depending upon which way the blade 12 is 95 moved.

In practice the bracket is secured to the back of the chair as shown in Figs. 1 and 2 so as to cause the free end of the bracket to be disposed directly above the seat of the 100 chair. When the occupant imparts rocking motion to the chair, the blade 12 being free to swing, the inertia of the blade will cause the same to oscillate or swing upon its pivot, thereby causing a fanning of the air in close 105 proximity to the occupant. Upon movement of the blade 12 rotary motion is imparted to the blades 11, first in one direction and then in the other, through the medium of the cord 13 as has been described. Thus 110 it will be seen that further fanning of the air is accomplished in addition to the mov-

ing of the blade 12. It has been found in practice that the rotary blades serve to keep flies and other troublesome insects out of the zone of the occupant, while the oscillating 5 blade 12 agitates the air sufficiently to keep the operator cool.

In Fig. 3 I have shown a modified form 10 of my invention, in which I have substituted a weight 15 of any suitable construction, in place of the blade 12. Owing to the fact that the weight 15 has less air resistance than the blade 12, a greater speed is imparted to the rotary blades, as will be understood. The weight 15 is substituted for the 15 blade 12 when it is desired to use only the rotary blades for agitating the air.

Although I have shown and described a specific form of fan, I wish it to be understood that various changes in the size, shape, 20 proportion and minor details of construction may be made without departing from

the spirit and scope of the appended claim.

What I claim is:—

A fan attachment for chairs comprising a bracket, a U-shaped yoke secured to one 25 extremity of said bracket, a bearing plate mounted upon said bracket and engaging the medial portion of said yoke, pulleys journaled in the opposite extremities of said yoke, a member pivotally mounted upon 30 said bracket between said pulleys and depending from said bracket, a shaft journaled in said bearing plate and having the opposite extremities thereof provided with blades, and a cord wound about said shaft 35 and passing over said pulleys and having the opposite extremities secured to the opposite sides of said member.

EMIL F. HERRMANN.
